Des. 206,046

Patented Oct. 18, 1966

206,046

NAIL PULLER

George Harold Seidlein, 996 Jessie Ave.,
Yuba City, Calif.

Filed Nov. 15, 1965, Ser. No. 88,097

Term of patent 14 years

(Cl. D93—4)

FIG. 1

FIG. 2

FIG. 3

FIG. 4

FIGURE 1 is a side elevational view of my new design for a nail puller;

FIGURE 2 is a top plan view thereof;

FIGURE 3 is a bottom plan view thereof; and

FIGURE 4 is an end elevational view thereof as seen from the right in FIGURE 2.

I claim:

The ornamental design for a nail puller, substantially as shown.
